[57] CLAIM

The ornamental design for a fryer, as shown and described.

DESCRIPTION

FIG. 1 is a front elevational view of a fryer according to my new design;

FIG. 2 is a rear elevational view thereof;

FIG. 3 is a left side elevational view thereof;

FIG. 4 is a right side elevational view thereof;
FIG. 5 is a perspective view thereof, seen from above and to the right;

FIG. 6 is a bottom plan view thereof; and,

FIG. 7 is a top plan view thereof.

The right and left sides of the illustrated fryer have projecting parts with recessed bottom surfaces to define handles. The front of the fryer is provided, near the bottom, with an on/off switch, a thermostat and a warning light. The center of the lid of the fryer has an arcuate handle with a timer at its upper surface. The lid is provided with narrow, curved apertures.
